Primary Examiner — Khawaja Anwar(74) Attorney, Agent, or Firm — Anooj Patel; Heber Martin Carbajal; Hankin Patent Law, APC(57) CLAIM

The ornamental design for a cookie tray, as shown and described.

DESCRIPTION

FIG. 1 is a top perspective view of a cookie tray, showing our new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines showing certain markings are for the purpose of illustrating environmental structure and unclaimed subject matter and form no part of the claimed design.
